UNITED STATES PATENT OFFICE.

CHRISTOPHER MATTICE, OF DELHI, NEW YORK.

STOVE.

SPECIFICATION forming part of Letters Patent No. 287,765, dated October 30, 1883.

Application filed August 22, 1883. (No model.)

To all whom it may concern:

Be it known that I, CHRISTOPHER MATTICE, a citizen of the United States, residing at Delhi, in the county of Delaware and State of New York, have invented certain new and useful Improvements in Stoves, of which the following is a specification, reference being had therein to the accompanying drawings.

My invention has relation to improvements in stoves, and more particularly to the grates thereof, and the object of the invention is to improve the construction and to economize fuel; and to that end the novelty consists in the construction and arrangement of the same, as will be hereinafter more fully described, and particularly pointed out in the claims.

In the accompanying drawings the same letters of reference indicate like parts of the invention.

20 Figure 1 is a longitudinal section of a stove with my improved grate applied thereto. Fig. 2 is a top plan view of the stove on the line *xx*. Figs. 3 and 4 are details of the grate-locking bar.

25 A is the top, B the bottom, C the front, and D the fire-wall, of the stove.

E is one of the grates, and its inner rear bar, *e*, is provided with a journal, *e'*, having a bearing in the bracket *F* in the center of 30 the fire-box, while the outer end of the bar *e* has a bearing in the side *H*, and extends outwardly, terminating in an angular shank, *h*, to receive the ordinary wrench or shaker for operating the grate.

35 I is a pawl provided with a slot, *i*, which slips over the stud *K* on the side *H*, which retains it in place against the side, but at the same time allows the pawl to swing around on said stud. The free end of the pawl *I* is 40 provided with a jaw, *k*, which engages with the shank *h*, to hold the grate in position when the stove is in use, and by placing a wrench on the shank *h* and raising the pawl the grate may be shaken or dumped at will.

45 L is a pin passing through a hole in the front *C*, and extending inward to form a rest or support for the grate. The pawl *I* being released from the shank *h*, the pin *L* may be drawn out and the coals dumped in the ash-50 pan *b*.

M is a removable partition in the center of the fire-box, being held in place by the guides

m m. This partition is provided with a draft-regulator, *m'*, and on the opposite side of the partition *M* is a grate, *E'*, having its rear bar, 55 *e*, provided with a journal, *e'*, having a bearing in the bracket *F*, and its outer end has a bearing in the side *H'*, and extends outwardly, terminating in an angular shank, *h*, to receive the shaking-wrench. The object of the 60 draft-regulator *m'*, which is located in the space formed between the upper end of the partition *M* and the lower side of the stove-top, is to regulate the size of that opening, whereby communication between the respective 65 fire-boxes may be enlarged, or virtually closed, as seen in Fig. 1. Thus it will be observed that when the fuel is burning only in one fire-box a portion of the heat arising therefrom may be allowed to escape into the 70 opposite fire-box, and thence over that portion of the stove to the rear, whereby articles may be kept warm in that side of the stove.

The grates *E* and *E'* are exact counterparts of each other, and are operated in the same 75 manner, though of course, being independent of each other, they can be operated separately. If necessary, the partition *M* can be removed and the divided fire-box thrown into one; or, when the partition is in place, only 80 one-half of the fire-box may be used, as is often desirable in summer weather; or fire may be made in both sections and used by separate parties for their individual cooking.

This case is confined to the novel features of 85 the fire-box. Other matter incidentally shown forms the subject of another application, Serial No. 96,159.

Having thus described my invention, what I claim is—

1. The combination, with the double grates *E E'*, of the partition *M*, having draft-regulator *m'*, as set forth.

2. The combination, with the removable partition *M*, guides *m m*, and grates *E E'*, having shanks *h h*, of the pawls *I*, having jaws *k*, as set forth.

In testimony whereof I affix my signature in presence of two witnesses.

CHRISTOPHER MATTICE.
